(57) **CLAIM**

The design for the casement window crank handle, as shown and described.

DESCRIPTION

FIG. 1 is a perspective view of the crank handle. The broken line shown on FIG. 1 is for illustrative purposes only and forms no part of the claimed design.

FIG. 2 is a side elevation of the crank handle shown in FIG. 1.

FIG. 3 is a front elevation view of the crank handle shown in FIGS. 1 and 2.

FIG. 4 is a rear elevation view of the crank handle shown in FIGS. 1, 2 and 3.

FIG. 5 is a top plan view of the crank handle shown in FIGS. 1-4; and,

FIG. 6 is a bottom view of the crank handle shown in FIGS. 1-5.

The broken line showing on FIGS. 2, 4 and 5 is for illustrative purposes only and forms no part of the claimed design.
